UNITED STATES PATENT OFFICE.

JOHN M. VAN HEUSEN, OF BOSTON, MASSACHUSETTS.

GARTER.

Application filed November 21, 1922. Serial No. 602,338.

To all whom it may concern:

Be it known that I, JOHN M. VAN HEUSEN, a citizen of the United States, and a resident of Boston, in the county of Suffolk 5 and State of Massachusetts, have invented certain new and useful Improvements in Garters, of which the following is a specification:

The present invention relates to improvements in garters, and more particularly to garters made wholly or in part of non-elastic fabric such, for example, as pile fabric of the nature described in my Patent No. 1,357,929 of November 2, 1920.

The purpose of my invention is to provide a garter having on the inner surface of the band portion thereof a pile fabric, the construction of said garter being such that the band portion thereof is free to adjust itself to any shape or size of leg or drawers leg, and also such that the pile surface of the band completely encloses the leg of the wearer and is in contact therewith at substantially all points including the portion at the front part of the garter, which in most garters consists of a triangular shaped piece of fabric to which the band and the sock supporting device are connected.

My invention will be more fully described in connection with the accompanying drawings, illustrative of one embodiment thereof in which,

Fig. 1 is a view showing my improved garter attached to the upper inner edge of a sock or stocking.

Fig. 2 is a view showing the garter of Fig. 1 when worn on a leg of a different size and shape.

Fig. 3 is an enlarged view showing the construction of the front portion of the garter.

Fig. 4 is an enlarged diagrammatical view showing one weave of a pile fabric in which the pile threads are at an angle to the body portion of the fabric.

Referring to Fig. 1, it will be seen that the sock or stocking 1 is supported by the garter 2, which is attached to the said sock or stocking by means of the grip 3. The band 4 is provided with a velvet, velveteen, or like pile fabric surface 5, and the pile threads of the said pile surface are inclined at an angle to the back or body portion of the band as shown in Fig. 4. The band is so arranged that when the garter is worn the pile threads on the inner surface of the

said band will project in a downward and inward direction. It will be seen that any tendency of the garter to slip downward will be resisted by the inclined pile threads. 60 In fact, it has been found that the expansion and contraction of the muscles of the leg encircled by the garter operates to produce an actual tendency for the garter to work upward on the leg or drawers leg of 65 the wearer. This upward movement, however, is not so pronounced as to make the garter uncomfortable, but is strong enough effectively to hold up the sock or stocking.

In garters of this type it is desirable in order to produce the most satisfactory and complete results, that the pile fabric be in contact with the leg at all points on the inner surface of the encircling band, and it is equally important that the said band be 75 permitted to adjust itself to the particular shape of leg on which it is worn. The garter shown in Figs. 1 and 2 is so constructed as to insure the maximum degree of supporting action from the pile fabric. As illustrated in Figs. 1 and 2, the end portion 6 of the band is secured to the pin 7 of the supporting strip 8 to form the pivot arrangement illustrated in detail in Fig. 3. and the free end portion 9 of the band is 85 provided with an eye 10 or similar device which is adapted to be attached to the pin 7. It will be seen that the pivoted end 6 of the band, as well as the free end 9 thereof, is 90 free to turn on the pin 7 so that the band can 95 adjust itself to the shape or form of the wearer's leg. Also the pile surface extends substantially entirely around the leg of the wearer and closes at the front so that a maximum area of contact is afforded.

In Figs. 1 and 2 my invention is shown on legs of different form and shape, and as indicated, the garter, in adjusting itself to the shape of the leg shown in Figure 1, takes on a somewhat different position from that which it has when on the leg shown in Fig. 2. It will be obvious that if the band 4 of the garter were permanently fastened in one position to the supporting strip 8 it would be prevented from adjusting itself to the wearer's leg and, consequently, the effective action of the pile threads on the said band would be interfered with.

Fig. 3 illustrates one way in which the attached end 6 of the band may be secured to the supporting strip 8, so that the said end 6 is free to rotate around said point of

attachment. The projections 11 and 12 near the base of the pin 7 limit the rotation of the pivoted end 6 of the band. That is to say, these projections prevent the end 6 of the band from turning completely around on the pin 7, but do not in any way hinder the band from adjusting itself to any type or shape of leg upon which the garter may be worn.

10 The reason for thus limiting the motion of the attached end 6 of the band is to make it impossible for a wearer inadvertently to apply the garter to his leg with the contact filaments of the pile fabric directed upwardly instead of downwardly. It will be apparent from Figs. 1 and 2 that in the absence of means for preventing the free rotation of end 6 of the band, the band might be placed around the leg in the wrong direction, that is, so the end 6 would be on the opposite side of the pin from that on which it is illustrated. If this were done the pile threads 5 instead of being downwardly and inwardly directed would point upwardly and inwardly and thus the garter, assisted by gravity and the action of the pile threads, would tend to work down the leg and fall off. In the garter construction of my present invention, however, this possibility is wholly avoided by the use of projections 11 and 12 or other similar means.

While I have illustrated and described only one embodiment of my invention, it will be understood that the invention may be carried out in other ways than that illustrated and described. The main characteristic feature of the invention is providing a garter of the band type having a suitable pile facing of the character described in my Patent #1,357,929, with a device which permits the movement and adjustment within defined limits of the garter band on the leg of the wearer, so that the maximum effective action of the pile surface is obtained, and also to provide a contact of the pile fabric at the front of the wearer's leg as well as at the side and rear portion thereof.

I am aware that it is well known in the art to provide a cord attachment on garters which serves to fasten or hold together the two ends of the band portion and also the sock supporting device, and I make no claim to such a garter.

The terms and expressions which I have employed are used as terms of description and not of limitation, and I have no inten-

tion, in the use of such terms and expressions of excluding any equivalents of the features shown and described, or portions thereof, but recognize that various modifications are possible within the scope of the invention claimed.

What I claim is:

1. In a band garter, the combination of a leg encircling band of pile fabric presenting on its inner surface contact filaments downwardly and inwardly inclined to the leg or drawers leg of the wearer, a sock supporting strip, a permanent pivotal connection between one end of the said leg encircling band and the said sock supporting strip, means for pivotally attaching the free end of the leg encircling band to the said pivotal connection, and means for limiting the pivotal motion of the permanently attached end of the leg encircling band without hindering the free adjustment of said band to the leg.

2. In a band garter, the combination of a non-elastic leg encircling band presenting on its inner surface contact filaments downwardly and inwardly inclined to the leg or drawers leg of the wearer, a sock supporting strip, a pin attached to said sock supporting strip, a permanent pivotal connection between said pin and one end of said leg encircling band, means for attaching the free end of said leg encircling band to the said pin and means on the sock supporting strip for limiting the pivotal motion of the permanently attached end of the leg encircling band without hindering the free adjustment of said band to the leg.

3. A non-elastic band garter adapted to adjust itself to any form or size of leg, comprising a leg encircling band provided on its inner surface with pile fabric presenting contact filaments downwardly and inwardly inclined to the leg or drawers leg of the wearer, a sock supporting strip having thereon a pin one end of said leg encircling band being pivotally attached to the pin on said sock supporting strip, the free end of the leg encircling band having thereon an attaching device adapted to pivotally connect said free end of said band with said pin, and two projections near the base of the said pin, which limit the pivotal motion of the attached end of the band and prevent the garter from being applied to the leg with the contact filaments upwardly directed.

JOHN M. VAN HEUSEN.
